COMBINED CIGARETTE CASE AND LIGHTER

Filed May 3, 1940

UNITED STATES PATENT OFFICE

2,235,335

COMBINED CIGARETTE CASE AND LIGHTER

George Philip Schmitt, New York, N. Y.

Application May 3, 1940, Serial No. 333,182

3 Claims. (Cl. 206—41.4)

This invention is a combined cigarette case and lighter.

A lighter contemplated herein is one which employs a catalyst for igniting cigarettes where-
5 in the vapor of alcohol or other vaporizable liquid carried by absorbent material is employed for effecting such action upon the catalyst, in the presence of atmospheric air, as will render such catalyst incandescent, so that the cigarette or
10 the like applied thereto and drawn upon, may be ignited; and further a lighter of such cata-
lytic type in which the cover is eliminated and the valve through which the mixture of vaporized
15 fuel and air must flow to the catalyst to render
it operative is automatically maintained in shut-
off position, and selectively opened for the light-
ing of the cigarette by depressing a slideable
member which extends from the bottom of the
20 lighter casing. It is imperative that when the
lighter is not in use the valve remain closed
(in which case the slideable member is in its
inoperative extended position), for it is known
25 that if the catalyst remains under the influence
of fuel vapor for a prolonged period in its in-
operative state condensation will form on the
catalyst, and render it inactive until the catalyst
has been dried out. The condensation is aggra-
20 vated by the fact that the atmospheric air which
is mixed with the fuel vapor carries moisture.
30 It is an object of the present invention to as-
sociate a catalytic lighter with a cigarette case
in a compact, convenient and neatly arranged
manner.

It is a further object of this invention to bring
35 about this association whereby the catalytic
lighter will always be positioned with respect to
the case such that the said slideable member will
remain in its inoperative extended position dur-
ing the time the lighter remains in the case.

40 It is a still further object of the present in-
vention to provide a seat in the case for a cy-
lindrical lighter of any convenient type and to
further provide openings in the cover and body
45 of the case through which the body of the lighter
will protrude and at which it will be held by the
cover and body of the case when the latter is
closed, the lighter providing means at said open-
ings for blocking the escape of loose cigarette
50 tobacco from the case into the pocket of the
user or the passage of dirt or dust into the case;
the opening in the body providing an entry for
the finger of a hand to raise the lighter off its
seat and thus facilitate its withdrawal for use
55 when the case cover is opened.

It is yet another object of the present invention to utilize a cylindrical lighter as embellishing means for the case at the cover and body openings thereof.

Another object of the present invention is to 5
provide a cigarette case for a cylindrical lighter
having spaced flanges defining openings in the
cover and body of the case at an end thereof, the
flanges supporting and holding the lighter in po-
sition.

With the aforesaid and other objects in view,
the invention consists in the novel combination
and arrangement of parts hereinafter more par-
ticularly described, pointed out in the subjoined
claims, and illustrated in the annexed drawing, 15
wherein like parts are designated by the same
reference characters or numerals throughout the
several views, and in which:

Fig. 1 is a perspective view of a combined cig-
arette case and lighter made in accordance with 20
the invention;

Fig. 1a is a sectional view taken along line
1—1a of Fig. 1;

Fig. 1b is a side view of the portion of the de-
vice shown in Fig. 1a;

Fig. 2 is a top view of the device shown in Fig.
1, but being in open position and drawn on a
somewhat smaller scale;

Fig. 3 is a sectional view taken along line 3—3
30 of Fig. 2;

Fig. 4 is a sectional view taken along line 4—4
of Fig. 2;

Fig. 5 is a sectional view taken along line 5—5
35 of Fig. 2;

Fig. 6 is a perspective view of a combined cig-
arette case and lighter embodying the invention
in a somewhat modified form.

Fig. 7 is a detail sectional view taken along
line 7—7 of Fig. 6; and

Fig. 8 illustrates a cigarette case embodying
40 the invention in a further modified form.

In the drawing there is disclosed a flat cig-
arette case 20 having a body portion 21 defined
by the side and end walls or flanges 22, 23, re-
spectively, within which may be contained cig-
arettes 24 held against the bottom 25 of the body
portion 21 by a conventional retainer member 26.
Hinged to a side wall 22 of the body portion 21
as by means of the hinges 27 is a cover portion 50
28 which may also have side and end walls 29,
30 respectively flushingly abutting against the
side and end walls 22, 23 respectively of the body
portion 21. Conventional complementary latch
or lock elements 31, 32 may be provided to main-
55

tain the cover 28 and body 21 in locked engagement. The cover and body of the cigarette case may be made of any suitable material, such as, plastic, metal, etc.

5 Preferably at one end of bottom 25 of body portion 21 there is provided a transverse opening 33 having the spaced preferably bevelled side edges 34 providing a seat for a cylindrical catalytic lighter 35. Lighter 35 has a slidable extension 36 which, when the lighter is in inoperative state protrudes from an end of lighter case 37. The length of opening 33 is at least equal to the combined length of cylindrical lighter casing 37 and valve extension 36 to avoid "jamming" of the lighter or inadvertent retraction of the extension 36 of the lighter when the lighter is seated on the edges 34; and the width of opening 33 is preferably less than the radius of casing 37. The portion of the lighter compartment or section 60 at the ends of the bottom opening 33 are preferably beaded or turned up at an angle as indicated at 61, 62 providing retaining guides for guiding casing 37 and extension 36 to transverse opening 33 and for retaining said casing and extension at said opening 33 against longitudinal movement. The lighter may be easily withdrawn from the cigarette case by the insertion of the finger of one hand of the user within the opening 33, which will 20 raise the lighter off its bevelled seat and then casually lifting the lighter with fingers of the other hand of the user, the lighter being guided by the members 61, 62.

35 The cover 28 likewise has at one end a transverse opening 40 similar to and which registers with the bottom opening 33 when the cigarette case is closed. This opening 40 has the spaced, preferably bevelled, side edges 41 which substantially engage the cylindrical wall of the lighter 40 when the cover is in closed position as seen in Figs. 1 and 1a, thereby holding the lighter in the cigarette case and maintaining the lighter substantially against movement.

The lighter when in this position acts as an 45 end closure, for the cigarette section 21' of the case substantially blocking the escape of loose cigarette tobacco from the case into the pocket of the user or the passage of dirt or dust into the case. Furthermore the cylindrical casing of the 50 lighter is utilized as an embellishment for the cigarette case as portions thereof protrude through the openings 33, 40 of the body and cover, respectively, of the cigarette case.

55 Figures 6 and 7 disclose the invention in a modified form. The cigarette case has a bottom portion 21a and a hinged cover 28a which may be similar in design to that disclosed in Figure 1. At the lighter compartment portion of the case the body 21a is provided with the spaced inwardly turned or upwardly extending flanges 63 and being held in position against lateral movement by the flanges 64 of cover 28a when the latter is in closed position.

The cover 28a and body portion 21a are made 65 deeper than the case of Figure 1 so as to accommodate a double layer of cigarettes 24, one layer 24c in the bottom 21' and another layer 24b in the case, the layers being separate from each other by divisional plates 62.

70 Figure 8 discloses the invention in a further modified form. This cigarette case 65 has three compartments in its bottom and cover portions 66 and 67, respectively. The end compartment 68 in bottom 66 and corresponding end compartment 69 in cover 57 (which may be similar in

construction to that heretofore disclosed) is provided for holding and retaining respectively, lighter 35. The intermediate compartment 70 in the bottom 66 to hold cigarettes and an end compartment 71 in the bottom 66 and corresponding end compartment 72 in the cover 67 for holding and retaining respectively, cigarette holder (not shown). The end compartments or sections 68 and 71 of the case are separated from the cigarette compartment 70 by the walls 73, 74, respectively. A cigarette retainer 75 is hinged at 76 to walls 73.

5 Although the drawing and the above specification discloses the best modes in which the invention is at present contemplated and embodied, it 15 is desired that the invention in no way be limited to the details of such disclosure, for in the further practical application of the invention many changes in the forms and proportions may be made as circumstances require or experience 20 suggests without departing from the spirit of the invention within the scope of the appended claims.

25 Having thus described the invention, what is claimed as new and desired to be secured by Letters Patent, is:

1. A combined cigarette case and lighter comprising in combination a lighter having a cylindrical housing and a movable valve extension at one end of said housing, and two oppositely dished case portions having a hinge connection therebetween, one of said portions providing a body having cigarette and lighter holding sections, the said lighter section being located at one end of said case, the other of said portions 35 providing a cover for said body, the said case portions having similar registering transverse substantially rectangular openings at said one end of said case through which portions of the said lighter housing and said extension protrudes when said other of said portions is in closed position, said lighter housing substantially engaging said case portions when said cover is in closed position whereby the lighter is held substantially against lateral movement, the said 40 transverse opening in said body permitting the finger of the hand of the user of the cigarette case to contact said lighter housing and to raise it out of said lighter holding section when said cover is in open position, said transverse opening in said body being in width less than the diameter of said cylindrical housing and at least equal in length to that of the combined length of said cylindrical housing and said extension of said lighter to prevent movement of said valve 50 extension relative to said cylindrical housing upon positioning of said lighter in said lighter holding section at said transverse opening in said body.

2. A combined cigarette case and lighter comprising in combination a lighter having a cylindrical housing and a movable valve extension at one end of said housing, and two oppositely dished case portions having a hinge connection therebetween, one of said portions providing a body having cigarette and lighter holding sections, the said lighter section being located at one end of said case, the other of said portions 65 providing a cover for said body, the said case portions having similar registering transverse substantially rectangular openings at said one end of said case through which portions of the said lighter housing and said extension protrudes when said other of said portions is in closed position, said lighter housing substantially 70

- engaging said case portions when said cover is in closed position whereby the lighter is held substantially against lateral movement, the said transverse opening in said body permitting the finger of the hand of the user of the cigarette case to contact said lighter housing and to raise it out of said lighter holding section when said cover is in open position, said transverse opening in said body being in width less than the diameter of said cylindrical housing and at least equal in length to that of the combined length of said cylindrical housing and said extension of said lighter to prevent movement of said valve extension relative to said cylindrical housing upon positioning of said lighter in said lighter holding section at said transverse opening in said body, said lighter providing an end closure for said cigarette holding section.
3. A combined cigarette case and lighter comprising in combination a lighter having a cylindrical housing and a longitudinally movable extension in said case, and two oppositely dished case portions having a hinge connection therebetween, one of said portions providing a cigarette and lighter holding body, the other of said portions providing a cover for said body, the said case portions having substantially similar registering transverse openings through which portions of the said lighter protrudes when said other of said portions is in closed position, the width of said transverse opening in said body being less than the diameter but no less than the radius of said cylindrical housing and the length of said transverse opening in said body being at least equal to that of the combined length of said cylindrical casing and said extension of said lighter to prevent substantial longitudinal movement of said extension relative to said cylindrical housing upon positioning of said lighter in said lighter holding section at said transverse opening in said body, said transverse opening in said body permitting the finger of the hand of the user of the cigarette case to contact said lighter and to raise said lighter out of said lighter section when said cover is in open position.
